MECHANICAL TIMER

Robert Sardeson, Minneapolis, Minn., assignor to
McGraw Electric Company, Chicago, Ill., a cor-
poration of Delaware

Application November 29, 1937, Serial No. 177,136

15 Claims. (Cl. 161—16)

My invention relates to timing mechanisms and particularly to mechanical timers for controlling the duration of an operating period of a toaster.

5 An object of my invention is to provide a novel, simple and highly efficient mechanical timer for mounting on an electric toaster.

Another object of my invention is to provide a mechanical timer adapted to operate at a plurality of different substantially constant speeds.

Another object of my invention is to provide a mechanical timer having a spring driven gear train and a retarding means normally engaged therewith and disengageable therefrom by thermally-actuable means to cause the timer to operate first at a relatively slow speed and then at a higher speed.

Another object of my invention is to provide a plural speed mechanical timer associated with a toaster to control the duration of an operating period thereof by operating at one speed for an initial period of time and then at a substantially higher speed, the instant of change from one speed to another being determined by thermal means subject to toaster temperature.

Still another object of my invention is to provide a mechanical timer associated with a toaster having a detent for holding parts of the toaster in operative position, the timer being operable in such manner as to make available substantially all of its power when acting on the detent to cause release thereof and termination of an operating period.

The novel features that I consider characteristic of my invention are set forth in the appended claims. The invention itself however both as to its organization and its method of operation together with different objects and advantages thereof will best be understood from the following description of a specific embodiment when read in connection with the accompanying drawings in which,

Fig. 1 is a view in vertical longitudinal section, taken on the line 1—1 of Fig. 2, through a toaster 45 having associated therewith a timer embodying my invention.

Fig. 2 is a view in vertical lateral section therethrough taken on the line 2—2 of Fig. 1 showing the front interior of a toaster, partly in elevation and partly in section,

Fig. 3 is a fragmentary sectional view on a slightly enlarged scale, taken on the line 3—3 of Fig. 7,

55 Fig. 4 is a side elevational view with the casing

broken away and parts of the timer shown in operated positions,

Fig. 5 is a view similar to that of Fig. 4 showing parts of the timer and one of the bread slice supports in the positions which they occupy at 5 the beginning of a toasting operation,

Fig. 6 is a fragmentary view in side elevation showing parts of the timer in the positions which they occupy at the end of the low speed operating period,

Fig. 7 is a fragmentary vertical longitudinal sectional view, on a slightly enlarged scale, taken on the line 7—7 of Fig. 2,

Fig. 8 is a fragmentary sectional view, on a slightly enlarged scale, similar to Fig. 7 but 15 showing the retarding means disengaged from the gear train,

Fig. 9 is a fragmentary view, slightly enlarged, taken on the line 9—9 of Fig. 12,

Fig. 10 is a fragmentary horizontal sectional view, slightly enlarged, taken on the line 10—10 of Fig. 4,

Fig. 11 is a fragmentary horizontal sectional view, slightly enlarged, taken on the line 11—11 of Fig. 7,

Fig. 12 is a fragmentary sectional view, slightly enlarged, taken on the line 12—12 of Fig. 7,

Fig. 13 is a fragmentary vertical sectional view, slightly enlarged, taken on the line 13—13 of Fig. 2, and

Fig. 14 is a fragmentary view, slightly enlarged, in side elevation of a modified form of certain parts of the timer.

An automatic electric toaster designated generally by the numeral 21 includes a skeleton base 35 frame 23 which may be made of a suitable molded composition material and which supports a metal bottom plate 25, which bottom plate may be secured in proper operative position in the frame 23 by a plurality of suitable screws 27. A crumb tray 29 may also be suitably secured to the skeleton frame 23 in a manner well known in the art.

I have elected to illustrate a two-slice toaster although I desire it to be understood that my invention is not limited thereto and is applicable 45 to a toaster adapted to toast any number of slices of bread at a time. The toaster as illustrated provides a pair of electric heating elements for each slice of bread to be toasted therein, each heating element including one or more thin plates 31 of electric-insulating material such as mica, on which a resistor wire or strip 33 is wound, and while the resistor is positioned on that side of its support adjacent to the slice of bread to be toasted thereby I do not wish to be 50 55

restricted thereto, as I may wind the resistor against each side of the plate 31. I provide also a plurality of vertically-extending guard wires 35 to space a slice of bread from the heating elements and to maintain it in proper centered position between the two heating elements.

The lower ends of the respective plates 31 of electric-insulating material may have interfitting engagement with the bottom plate 25, while the upper edges thereof may be held by top frame plates 37 extending longitudinally of the toaster and by depending return-bent upper portions of the guard wires 35 in a manner now well known in the art.

15 The toaster includes also a rear intermediate plate 39 and a front intermediate plate 41, a toasting chamber being constituted by the front and rear intermediate plates and the outer vertically-extending heating elements. The toaster 20 is further provided with an outer casing comprising vertically-extending walls 43 and a cover member 45, the cover constituting the top wall of the toasting chamber and the base plate 25 constituting the bottom closure therefor. Side walls 25 or baffle plates 46 located between the outermost heating elements and the side walls of the casing may also be provided.

25 A plurality of vertical standards 47, here shown as three in number, are positioned in a mechanism chamber 49 defined by the front intermediate wall 41 and the front wall of the casing 43, the lower ends of these standards being supported by plate 25 while the upper ends are supported and held in proper operative positions by forwardly extending portions of the top frame plates 37 and by a crossbar 51 (see Figs. 1 and 2). A carriage 53 is adapted to move vertically on the intermediate standard 47, a plurality of rollers 55 being mounted thereon and engaging the standard to reduce friction therebetween.

30 A slider 57 is vertically movable on the right hand standard 47 and a similar slider 59 is vertically movable on the left hand standard 47. Slider 59 has secured thereto a slotted plate 61 (see particularly Fig. 1) whereby to control a switch arm 63 which is insulatedly pivotally mounted on a bracket 67 supported on front intermediate plate 41. Switch arm 63 is adapted to engage with and be disengaged from a fixed 35 contact member 69 insulatedly supported on front intermediate plate 41 to control the energization of the hereinbefore described heating elements. An actuating knob 71 is mounted on carriage 53 outside of the casing to permit an operator to move it downwardly thereby moving downwardly carriage 53 and the two sliders 57 and 59.

35 A bread slice support 73 is positioned between each pair of heating elements and the two supports are mechanically connected with the sliders 57 and 59 as seen more particularly in Fig. 10 of the drawings, a crossbar 75 extending therebetween (see Fig. 10). A biasing means comprises a coil spring 77 positioned below the base plate 25, having one end thereof connected to the base plate 25 while the other end thereof is connected to a short arm 79 of a bellcrank lever which is pivotally supported at 81 on the rear intermediate plate 39. The bellcrank lever 40 includes also a longer arm 83 the forward end of which is slotted as at 85 (see Fig. 1) the crossbar 75 being adapted to move in this slotted end. Spring 77 biases the bread slice supports to upper or non-toasting position and switch arm 63 to 45 open position. Downward movement of knob 75

5 moves the bread slice supports into their lowermost or toasting position and simultaneously causes closing of the switch. All of the hereinbefore described details are well known in the art and reference may be had to Ireland Patent No. 2,001,362 for detailed descriptions thereof. It is to be noted that knob 71 and the movable parts associated therewith, are moved through a fixed distance at each operation and that the timer spring is therefore wound up a predetermined amount irrespective of the duration of a toasting operation or of the duration of operation of the timer.

10 In order to obtain automatic operation of a toaster embodying the hereinafter described timer and to provide variable durations of operating periods in accordance with the temperatures of the toaster I provide a novel timing mechanism designated generally by the numeral 87 which timing mechanism is positioned in the 15 mechanism chamber 49 hereinbefore described.

20 This mechanical timer includes a pair of side plates 89 and 91 held in spaced position by suitable spacing rods 93 in a manner well known in the art. A clock spring 95 (Fig. 12) has one end secured to a spring arbor 97 while its other end may be secured to a short pin 99 (Fig. 2) mounted on side plate 91. Arbor 97 has secured thereon at its other end, a pinion 101 which is in engagement with a vertically movable rack bar 103 which rack bar is moved downwardly when knob 71 is moved downwardly as is clearly set forth in Ireland Patent No. 2,001,362. A grooved roller 105 holds the rack bar 103 in proper operative position and in mesh with pinion 101. A 25 ratchet wheel 107 cooperates with a pair of pawls 109 to permit of winding up spring 95 by downward movement of knob 71 as is already well known in the art. The pawls 109 are mounted on a gear 111 which meshes with a 30 pinion 113 which is fixedly mounted on the same shaft as is a second gear 115. Gear 115 meshes with a pinion 117 fixedly mounted on the same shaft as is a gear 119. It is to be noted that these gears and pinions constitute a gear train. It 35 is to be noted that while I have illustrated a spring as constituting the prime mover my invention is not limited thereto as any other source of mechanical power may be used.

40 A retarding means adapted to be normally in engagement with the gear train includes a pivotally mounted reciprocable balance wheel 121 of the kind disclosed and claimed in my co-pending application Serial No. 152,580, filed July 8, 1937 and assigned to the same assignee as is the present application. Balance wheel 121 may be fixedly mounted on a shaft 122 rotatably supported inside plates 89 and 91. Reciprocating turning movement of balance wheel 121 is effected by a short lever arm 123 45 pivotally mounted on shaft 122, one end of which has connected thereto one end of a coil spring 125, the other end of which is connected to balance wheel 121. The other end of lever arm 123 has connected thereto a connecting rod 127 50 which is connected to a rotatable crank pin 129 on a crank disc 131. This crank disc is fixedly mounted on the same shaft which supports a pinion 133 (see Fig. 3), which pinion is normally in mesh with gear 119. The shaft carrying crank 55 disc 131 and pinion 133 is pivotally mounted in a swinging frame including side bars 135 and 137 which bars swing on a shaft 139 pivotally mounted in the two side plates 89 and 91.

60 It will be noted, by reference to Figs. 7 and 8

75

of the drawings, that during the unwinding of the spring 95 gear 119 turns in a clockwise direction and that the tendency of the force transmitted thereby to pinion 133 tends to move the pinion out of engagement with the gear 119. I have found this to be an important part of the design and construction of my improved mechanical timer in that the amount of force required to effect this disengagement is relatively small.

The method of operation of my improved mechanical timer is substantially as follows:

The retarding means above described is initially in engagement with the gear train for 15 a length of time dependent on the duration of an operating period and upon the temperature of the toaster. It is well known that a toaster of this general type must be operated for a certain relatively long period of time in an initially 20 cold toaster to obtain the desired degree of toasting of one or more slices of bread but that this operating period decreases in length with increase in temperature. It is obvious, for instance, that if a mechanical timer of the kind 25 thus far described had an operating period of say three minutes and that the duration of an operating period of the toaster were also three minutes, it would be necessary for the timer to operate at the slow speed during the 30 entire operating period of the toaster. It is further obvious that the period of operation of the timer at the slow speed decreases with the increase in the temperature of the toaster. I have found it desirable to determine the instant 35 of change-over from low to high speed by thermal means and to effect this change-over by mechanical means energized by the timer spring, and the mechanism for doing this will now be described in detail.

40 A disc 141 (see particularly Fig. 12 of the drawings) is fixed on spring arbor 97 outside of spring 95 to turn therewith and it may be noted that this arbor turns through substantially 480° in one direction while the spring is being wound 45 up, and in the opposite direction during unwinding of the spring which occurs during the operating period of the timer. This disc 141 has a spiral slot 143 therein which slot is adapted to receive a pin 145 fixedly mounted at one end of 50 a lever arm 147 which lever arm is pivotally mounted intermediate its ends as on a fixed pivot 149 supported by outer side plate 91 of the timer. Fig. 5 of the drawings shows the position of the disc 141 and particularly of the spiral slot 55 143 therein and of the lever arm 147, just after knob 71 has been moved downwardly to the full limit of travel thereof.

Shaft 139 of the swinging support has fixedly secured thereon at its outer end a shouldered latch 60 151 which latch may be of the shape shown in Figs. 4, 5 and 6 of the drawings. A pivotally mounted detent 153 is supported by outer side plate 91 and has a lower sharp end 155 adapted to fit into the shouldered upper end of latch 151. 65 Detent 153 is biased to latch-engaging position by a spring 157 (see Fig. 4).

Lever arm 147 has pivotally mounted thereon an arm 159, of substantially L-shape, the two parts thereof being of different lengths. The long 70 arm is pivotally mounted at its outer end on lever arm 147 intermediate the ends thereof and below pivot pin 149. A short pin 161 secured to arm 159 extends laterally inwardly therefrom for engagement with a cam surface 163 of detent 153 in a manner to be hereinafter described. Lever arm 75

147 has secured thereto at its lower end a latch-returning spring bar 165 which is adapted to engage latch 151 to cause movement thereof in a clockwise direction to thereby cause re-engagement of pinion 133 with gear wheel 119.

A bimetal element 167 which may be of the kind disclosed and claimed in my copending application Serial No. 127,100, filed February 23, 1937 and assigned to the same assignee as is the present application and now Patent No. 2,171,895 10 granted Sept. 5, 1939, is provided. This bimetal element is supported by a bracket arm 169 which is slidably mounted against outer side plate 91 and which may be moved manually upwardly and downwardly by an actuating knob 171 in a manner set forth in my copending application Serial No. 152,580, filed July 8, 1937 and assigned to the same assignee as is the present application. It may be noted that bimetal element 167 is positioned adjacent to the toasting chamber, in an 15 opening in one of the baffle plates 46 and is subject to high temperature radiant heat from one of the hereinbefore described heating elements.

The bimetal element 167 is so designed and constructed that it will flex in a downwardly direction when subjected to an increase in temperature and its outer free end has secured thereto a bent bar 173, the outer end of which fits into the forked end 175 on the short arm 159.

Fig. 6 of the drawings shows the positions of the actuating knob 171 and of the lever arm 147 as well as of bimetal element 167 when the toaster has been heated to say its normal operating temperature and immediately after release of the retarding means from the gear train. It will be noted, by reference to Fig. 6 of the drawings, that the spiral slot 143 has been moved from its original position to a certain extent so that pin 145 is positioned therein intermediate the ends of the slot. Lever arm 147 has been turned on its pivot pin 149 in a counter-clockwise direction thereby causing movement of arm 159 toward the left. Bimetal element 167 has simultaneously caused a turning movement of arm 159 in a clockwise direction so that pin 161 thereon was brought 45 into engagement with the cam surface 163 of detent 153, the result being that turning movement of lever arm 147 in a counter-clockwise direction caused an increase of pressure between pin 161 and cam surface 163 until finally detent 50 153 and particularly the lower sharp end 155 therefrom was moved out of engagement with latch 151. This resulted in quick disengagement of pinion 133 from gear 119, because of the direction of the force transmitted to pinion 133, and a sudden speeding up of the gear train.

Downward movement of knob 71 is utilized to wind up timer spring 95, carriage 53 being provided with a projection 180 for engaging a lug 180A at the lower end of rack bar 103. The rack bar is moved upwardly by the timer during unwinding of spring 95, and a cam surface 181 on projection 180 engages a lug 183 on a latch arm 185 to cause turning movement thereof. The lower end of arm 185 provides a detent 186 for engaging with a projecting portion 187 of slider 57, whereby the bread slice supports are held in toasting position and the contacts are held in circuit closing position during a toasting operation. 70 These details are disclosed and claimed in Ireland Patent No. 2,001,362.

It is thus obvious that the timer embodying my invention is operative at a relatively low speed for the major part of an operating period of the 75

toaster and that substantially the entire force of the spring is available to cause movement of the latch arm 185 which holds parts of the toaster in their operative positions to cause energization of 5 the heating elements and toasting of a slice of bread.

Referring now to Fig. 14 of the drawings I have there illustrated a modified form of detent 191 having a notched cam surface 193 instead of a 10 smooth surface as was shown in the other form thereof. Arm 159 may be provided with a relatively sharp-cornered pin 195 for engagement with one of the notches in the surface 193 thereby increasing the definiteness of engagement between 15 pin 195 and the detent to cause releasing movement thereof. In all other respects the parts associated with the parts shown in Fig. 14 are the same as have already been hereinbefore described.

20 It will be noted that the device embodying my invention provides a new method of control of an automatic toaster to vary the duration of an operating period of the toaster. A mechanical timer is operable at a relatively slow fixed speed 25 for a major portion of the duration of a toasting operation and is then operable at a relatively higher fixed speed for the remainder of said duration thereby making available substantially all of the power of the spring for effecting release of 30 mechanism or parts held in certain definite positions during a toasting period or for returning such parts to their normal positions. The instant of change-over from one speed to another is determined by a thermostat subject to toaster 35 temperature thus distinguishing from a method in which a thermally-controlled variable speed timer is used. The device embodying my invention provides releasing means energized by the timer itself and a thermal control means responsive to toaster temperature for determining the absolute and the relative lengths of time of operation of the timer of the different speeds during an operating period.

It is obvious further that while I have described 45 a two-speed timer I am not limited thereto, but by the application of the same principles can provide a plurality of different substantially fixed speeds. It is in this particular respect that the operation of my device distinguishes clearly from 50 a variable speed timer such as is already well known in the art and which has been applied to electric automatic toasters of this general type.

While I have illustrated one form of latch-releasing lever arm 147 actuated by the timer, I 55 do not desire to be limited thereto, since the function of this lever arm is to provide a power member driven by the timer and movable in a definite path to energize an actuating means for effecting release of a latch.

60 Another feature of the device herein disclosed and claimed is that the timer spring can unwind fully after each toasting operation and before the initiation of the next following toasting operation. The resistance to be overcome by an 65 operator when moving the actuating knob downwardly is not subject to a sudden increase as is the case where a mechanical timer is used, which operates at a fixed speed during the entire toasting operation, which toasting operation may be 70 terminated before the spring has been fully unwound.

Various modifications may be made in the device embodying my invention without departing from the spirit and scope thereof, and I desire 75 therefore that only such limitation shall be placed

thereon as are imposed by the prior art or as set forth in the appended claims.

I claim as my invention:

1. In a timing mechanism for causing other mechanism to operate after a time interval, a 5 spring gear train, a retarding means including a balance wheel and a pivotally mounted pinion normally meshing with a gear of said gear train and operating said balance wheel, a detent for holding said pinion in mesh with said gear and means energized by the spring for effecting movement of said detent and consequent disengaging movement of said pinion from said gear.

10 2. In a timing mechanism adapted to cause other mechanism to operate after a time interval, a power driven gear train, a retarding means including a balance wheel and a pivotally mounted pinion normally meshing with a gear of said gear train and operating said balance wheel and thermally-controlled means moved by the timing mechanism for effecting pivotal movement of said pinion to disengage it from said gear.

15 3. In a timing mechanism adapted to cause other mechanism to operate after a time interval, a spring driven gear train, a retarding means therefor including a balance wheel actuatable by a pivotally mounted pinion normally meshing with a gear of said gear train, a detent for holding said pinion in mesh with said gear, a lever arm actuatable by the timing mechanism, means pivotally connected with the lever arm for engaging the detent to effect release thereof, and thermally-actuable means acting on said pivotally connected means for determining the time of 20 release of said detent.

35 4. A timing mechanism as set forth in claim 3 and including a manually operable means to wind up said spring and cause simultaneous movement of said lever arm and movement of said pivotally mounted pinion into engagement with said gear 40 wheel and into latching position.

45 5. In a mechanical timer for mounting on an electrically heated automatic toaster having a bread slice support and a control switch spring-biased respectively to non-toasting and to open 50 positions and movable respectively to toasting and closed positions and detent means for holding the bread slice support in toasting position and the switch in closed position, said timer effecting release of said detent after a time interval and including a spring driven gear train, a retarding means normally connected with the gear train to cause said gear train to operate at a substantially fixed relatively slow speed and thermally-actuable means subject to toaster 55 temperature for effecting disengagement of said retarding means from said gear train to effect operation of said gear train at a higher speed and application of substantially the full power of the spring to effect release of said detent.

60 6. A timer as set forth in claim 5 in which the retarding means is urged to disengaged position by said gear train and is moved to engaged position simultaneously with movement of the bread slice support to toasting position and the switch 65 to closed position.

7. A timer as set forth in claim 5 and including a detent for holding said retarding means in engaging position and means energized and moved by said spring to cause releasing move- 70 ment of said detent.

8. In a timing mechanism adapted to cause other mechanism to operate after a time interval, a power driven gear, a retarding means to cause said gear to operate at a substantially fixed rel- 75

- atively low speed, said retarding means including a pivotally supported pinion normally in mesh with said gear, detent means to hold said pinion in mesh with said gear and thermally-controlled power means energized by the timing mechanism to act on and release said detent means to cause disengaging movement of said pinion from said gear to cause said gear to operate at a relatively high speed.
- 5 9. In a timing mechanism adapted to cause other mechanism to operate after a time interval, a spring driven gear, a retarding means to cause said gear to operate at a relatively slow speed, said retarding means including a pivotally supported pinion normally in mesh with said gear and a balance wheel having a fixed support, means connecting the balance wheel to the pinion to cause actuation of the balance wheel by the pinion, a detent for holding said pinion in mesh with said gear and thermally-controlled means energized by the timing mechanism to engage and move said detent to effect disengaging movement of said pinion from said gear to cause said gear to operate at a relatively high speed.
- 10 10. In a timing mechanism adapted to cause other mechanism to operate after a time interval, a power driven gear train including a swingably mounted retarding means to cause the gear train to operate at one substantially fixed speed, a detent for normally holding said retarding means in proper operative position and thermally-controlled means actuated by the timing mechanism for causing release of said detent and a disconnecting movement of the retarding means and operation of the rest of the gear train at a higher speed.
- 15 11. In a timing mechanism adapted to cause other mechanism to operate after a time interval, a power driven gear train, a retarding means including a balance wheel and a pivotally mounted pinion normally meshing with a gear of said train, a mechanical connection between said pinion and said balance wheel, means supporting said pinion for movement away from and toward said gear, means for holding said pinion in mesh with said gear and thermally-responsive means acting on said holding means and including a lever arm actuatable by the timing mechanism for causing movement of said pinion to disengage it from said gear.
- 20 12. A device as set forth in claim 9 and including means to wind up said spring and cause movement of said pinion into mesh with said gear.
- 25 13. In a timing mechanism adapted to cause other mechanism to operate after a time interval, a spring driven gear train, a retarding means therefore including a balance wheel, a fixedly supported shaft on which said balance wheel is mounted, a pivotally mounted pinion normally meshing with a gear of said gear train, means connecting the pinion to said balance wheel to actuate the latter, a detent for holding the pinion in mesh with said gear and having a cam surface, a lever arm supported solely by said timing mechanism and actuatable thereby, means pivotally connected with the lever arm for engaging the cam surface of the detent to effect release thereof and thermally-actuable means supported solely by said timing mechanism and acting on said pivotally connected means for determining the time of release of said detent.
- 30 14. A device as set forth in claim 13 and including a means to wind up the spring and cause simultaneous movement of the lever arm and movement of the pinion into mesh with said gear and into latching engagement with said detent.
- 35 15. In a timing mechanism for mounting on an electrically heated automatic toaster to determine the duration of an operating period thereof, said timing mechanism including a spring driven gear train operable initially at a substantially fixed relatively slow speed, a pivotally mounted pinion normally meshing with a gear of said gear train, a detent for holding the pinion in mesh with the gear of said gear train, a balance wheel, a shaft on which said balance wheel is mounted and having a fixed support, a connecting rod connecting the balance wheel and the pinion to cause oscillation of the balance wheel by the pinion and thermally-actuable means responsive to toaster temperature energized by said timing mechanism to cause release of said detent to cause disengaging movement of the pinion from the gear and operation of the gear at higher speed.
